UNITED STATES PATENT OFFICE.

JAMES P. MASON, OF PHILADELPHIA, PENNSYLVANIA, ASSIGNOR OF ONE-HALF TO THOMAS M. MOORE, OF SAME PLACE.

NUT-MACHINE.

SPECIFICATION forming part of Letters Patent No. 256,845, dated April 25, 1882.

Application filed May 2, 1881. (Model.)

To all whom it may concern:

Be it known that I, JAMES P. MASON, of the city and county of Philadelphia, in the State of Pennsylvania, have invented certain new and useful Improvements in Nut-Machines, of which improvements the following is a specification.

The object of my invention is to enable a series of nuts to be simultaneously cut and punched from a continuous blank or bar without waste of metal beyond that of the cylindrical punchings removed in the formation of the openings in which the screw-threads are to be formed.

To this end my improvements consist in sundry novel devices and combinations of mechanism hereinafter set forth, the same embracing a pair of shearing and punching die-boxes, each having a series of punches and abutments alternately located throughout its length, the punches of one die being located opposite the abutments of the other; mechanism whereby the dies are alternately pressed together upon the nut-blank and withdrawn therefrom; reciprocating grippers for holding the nut-blank in position to be acted upon by the dies; devices for relieving the punches from the cut and punched nuts, and mechanism for discharging the cut and punched nuts into a proper receptacle.

In the accompanying drawings, Figure 1 is a side view, partly in section, of a nut-machine embodying my improvements; Fig. 2, a vertical longitudinal section through the same at the line 1 1 of Fig. 3; Fig. 3, a horizontal section at the line 2 2 of Fig. 2; Fig. 4, a vertical transverse section at the line 3 3 of Fig. 2; Fig. 5, a similar section at the line 4 4 of Fig. 1; and Fig. 6, a side view, in elevation, of the backing-plate.

To carry out my invention I provide a substantial metallic frame, A, which is formed in two sections, firmly connected by bolts *a*, and is secured by bolts to a proper foundation. A head or carrier, B, is mounted in each section of the frame A, each head serving to receive one of the multiple shearing and punching die-holders or boxes, to be presently described, and one or both being susceptible of horizontal

reciprocation between guides A' upon the frame. 50 In the instance illustrated two movable heads are employed, and such construction will be herein described; but, if preferred, one of the heads may be made stationary and the other movable, a longer traverse being of course required in the latter case.

A horizontal driving-shaft, C, to which power is communicated from a prime mover, is supported in bearings *e* upon one side of the machine parallel to the longitudinal central plane 60 thereof, and carries two worms, *c' c'*, each of which meshes with a worm-wheel, C', fixed upon a transverse shaft, C², mounted in bearings in the frame A, and having eccentrics *c²* secured upon it adjacent to each of its bearings. Each of the eccentrics *c²* fits within a yoke, B', formed in a lateral prolongation of the heads B, and by the rotation of the shafts C² reciprocating movement is imparted to the heads B toward and from the intermediate 70 vertical central plane of the machine. A die-box, D, is fitted to each of the heads B, and a set of punching and shearing dies are secured thereto by caps D', having downwardly-projecting keys *d*, so that the dies may be readily 75 insertible and removable, and be firmly held when in position, each of said sets consisting of a series of punches, *d'*, and abutments *d²*, arranged alternately in the die-boxes.

The metal of the punch-dies is recessed or 80 dished out around the bases of the punches *d'*, so as to give the proper form to the tops of the nuts, and the abutment-dies *d²* are perforated by a central opening, which gradually increases in diameter from the front to the back of the 85 die, so as to admit of the free and unobstructed discharge of the metal removed by the punch of the opposite die-box, each of the abutments in one die-box being located in the same axial line as one of the punches in the opposite die-box.

The several dies of each series are held in position in their respective boxes by tongues, which enter corresponding grooves in the die-box and its cap, and by stout metallic backing-plates 95 *d³*, perforated with openings corresponding in location and dimensions with those of the punching-dies and with the strippers presently to be

described, the upper and lower sections and the backing-plates being clamped together by the caps D' of the die-boxes. The cut and punched nuts are discharged from the punches by stationary strippers E , which are plates of metal having T-heads, by which they are retained in position in bars e , slotted vertically to admit the heads of the strippers. Each of the bars e is fitted in a recess in the frame A 10 behind one of the heads B , and, with the strippers E held therein by a removable cap, e' , is inserted and removed with the die-box, to which its strippers are applied.

The strippers E are located one on each side 15 of each of the punches d' , passing through slots in the backing-pieces d^3 and recesses in the punch-dies, and, inasmuch as the distances between these slots are governed by the diameters of the nuts to be formed, any change in 20 the size of the dies for the purpose of making larger or smaller nuts must be accompanied by a corresponding change in the backing-pieces d^3 and stripper-bars e , separate pairs of backing-pieces, stripper-bars, and sets of strippers being provided for use with each of the 25 several pairs of die-boxes employed.

The metal blank from which the nuts are to be formed is inserted through an opening in one side of the frame A , and is presented to 30 the faces of the dies and clamped firmly in proper position relatively thereto during the shearing and punching operation by two grippers or clamping-bars, F F' , which are located parallel to the faces of the dies and above and 35 below the same, their vertical central plane coinciding with the plane of contact of the two sets of dies when pressed together by the movement of the heads. The grippers F are supported in sliding frames F' , fitted between 40 horizontal guides on the outside of the main frame A of the machine, by pins f on their ends, which pins enter slots f' in the frames F' . The slots f' are, for a portion of their length, parallel and horizontal, and are divergent for the remainder, and each of the frames F' is coupled to the strap f^2 of an eccentric, 45 f^3 , on one of the shafts C^2 , which reciprocate the heads longitudinally during the rotation of said shaft. By reason of the relation of 50 the pins f of the grippers to the slots f' vertical movement is imparted to the grippers F during the traverse of the pins through the inclined portions of the slots, coincidently with the horizontal movements of the sliding frames 55 F' and die-boxes D , the grippers being clamped upon the nut-blank, and there remaining stationary during the shearing and punching operation, at which period the pins are within the parallel portions of the slots.

60 For the purpose of compensating for wear of the clamping-faces of the grippers, as well as to admit of adjustment to blanks of different widths, each of the grippers may be provided with an adjustable clamping-jaw, secured by 65 bolts passing through vertical slots, so that its distance from the face of the gripper may be

regulated as required. The cylindrical cores punched from the nuts pass out through the central perforations of the abutment-dies d^2 into openings in the die-boxes communicating therewith, from which they fall on the inward traverse of the heads into suitable receptacles, and the cut and punched nuts are pushed off the lower gripper by a discharger, G , the same consisting of a rod parallel and adjacent to the 70 clamping-face of the lower gripper, and having two downwardly-projecting arms, the lower ends of which are pivoted to the main frame. The discharger is drawn clear of the gripper, on the upward movement of the latter, by a spring, 80 g , and on its downward movement is swept across the clamping-face, thereby pushing off the nuts which rest thereon, by a pin, f^4 , which projects from the lower side of the gripper and bears against a lever-arm, g' , formed upon 85 or secured to the lower end of one of the supporting-arms of the discharger.

In the operation of the machine the nut-blank, which is clamped between the faces of the adjustable jaws of the grippers, is sheared 90 into a series of nuts by the edges of the abutment-dies in the inward traverse of the heads, and the holes in the series of nuts are simultaneously punched, the punches in each die-box acting against the abutments in the other. 95 Upon the outward traverse of the heads the nuts are pushed off the punches by the stationary strippers and delivered to the lower gripper, from which they are discharged into a receptacle provided for them, and a new blank 100 being introduced, the operation is repeated.

It will be understood that in practice a pair of die-boxes and stripper-bars, each fitted with dies and strippers, as described, is to be provided for each diameter of nuts which it is desired to manufacture, and the insertion and removal of these parts can be readily and speedily effected whenever required. It will be further obvious that the machine is equally adaptable to the manufacture of washers from 105 blanks of less thickness than those used in the manufacture of nuts without departure from the spirit of my invention.

I am aware that the formation of nuts from a bar or blank by the action of two sets or series of alternately-arranged cutting and punching dies upon said blank while held between movable clamping-plates, as in the patent of R. Griffith, No. 16,142, dated December 2, 1856, is not new, and do not therefore broadly claim 115 said devices, either singly or combined. The machine of said Griffith patent, however, differs substantially from my invention in the particular that it does not embody the facilities for ready adaptation to the manufacture 120 of nuts of different desired sizes which I provide by my removable die-cases, each carrying its adjusted series of shearing and punching dies, as also in sundry details of the mechanism employed and specifically claimed by me. 125

I claim as my invention and desire to secure 130 by Letters Patent—

1. In a nut-machine, a multiple shearing and punching device consisting of two series of dies arranged in separate die-cases, each of said series being composed of alternate cutting-off and punching dies placed side by side in said cases, and mechanism to actuate said series of dies reciprocally toward and from one another, substantially as set forth. 30
2. In a nut-machine, the combination of a series of alternate shearing and punching dies, a case or die-box, a backing-plate, and a clamping cap or cover, substantially as set forth. 35
3. In a nut-machine, the combination of a movable series of alternate shearing and punching dies and a stationary series of strippers for discharging the cut and punched nuts, said strippers being arranged in pairs on each side of and parallel to each of the punching-dies, substantially as set forth. 40
4. In a nut-machine, the combination of a frame, a head or carrier fitted to guides therein, a die-box secured removably in said head and carrying a series of alternate shearing and punching dies, and a driving-shaft by which reciprocating movement is imparted to the head or carrier, substantially as set forth. 45
5. In a nut-machine, the combination of a pair of heads or carriers, each provided with a series of alternate shearing and punching dies, a pair of grippers or clamping-jaws intermediate between the heads or carriers, and a pair of sliding frames having inclined slots receiving pins on the ends of the clamping-jaws, substantially as set forth. 50
6. In a nut-machine, the combination of a pair of reciprocating grippers or clamping-jaws and a discharger traversing intermittently over the face of one of said grippers, substantially as set forth. 55
7. In a nut-machine, the combination, with a pair of heads or carriers, each provided with a removable die-case having secured within it a series of alternate shearing and punching dies, of mechanism by which said die-cases are actuated reciprocally toward and from one another, stationary stripper-plates for relieving the punching-dies, and a pair of grippers or clamping-jaws reciprocated between the heads and at right angles to their line of traverse, these members being combined for joint operation substantially in the manner and for the purposes set forth. 60
